UNITED STATES PATENT OFFICE

FRANK E. GRUNWALDT, OF SEATTLE, WASHINGTON

GAS FURNACE

Application filed March 29, 1928. Serial No. 265,770.

The invention is a furnace that is particularly adaptable for burning gas in which the wall of the fire box is corrugated or formed with channels and a central air heating chamber is provided in the center of the fire box with a conical lower end which deflects the hot gases outward so that they will pass upward through the corrugations or channels in the walls of the fire box.

The object of the invention is to provide a furnace, the interior of which is so arranged that gas may be used as fuel and at the same time the fuel cost kept below the average.

Another object of the invention is to provide a gas heating furnace in which practically all of the heat units may be extracted from the gas.

Another object of the invention is to provide a heating furnace in which air is circulated through and around the fire box.

Another object of the invention is to provide a heating furnace in which the wall of the fire box is provided with corrugations or comparatively deep channels into which the hot gases are deflected so that the hot gases will travel upward through the channels.

Another object of the invention is to provide a furnace in which the wall of the fire box is provided with corrugations or comparatively deep channels so that the heating surface is considerably multiplied.

Another object of the invention is to provide a combination of a fire box having a corrugated wall with a central heating chamber in the center of the fire box thereby considerably multiplying the direct heating surface.

Another object of the invention is to provide means for forming a joint in the wall of a furnace casing which will permit the casing to be opened so that the entire interior may be withdrawn without moving the casing or the flue connections thereto.

Another object of the invention is to provide means for connecting the upper and lower ends of the side walls of channels in the wall of a furnace fire box to permit drainage and expansion with simplicity.

Another object of the invention is to provide means for connecting the side walls of a

furnace casing to the furnace front through which the side walls will be drawn or stretched as they are clamped in place.

A further object of the invention is to provide means for constructing the interior of a furnace so that the gases from the flames will pass upward and be deflected outward into the corrugations or channels in the wall of the fire box and then pass downward to a flue opening.

A still further object of the invention is to provide a furnace having a central air heating chamber with a conical shaped lower end which is provided with intake passages through the lower end, the cross sectional area of which is equal to the cross sectional area of the chamber.

And a still further object of the invention is to provide a gas furnace which provides economical gas consumption and which is of a simple and economical construction.

With these ends in view the invention embodies a furnace having a fire box with walls having corrugations or channels, a central chamber with a conical shaped lower end having passages extending therefrom through the wall at the lower portion of the fire box, a flue extending from the said fire box, and an outer casing having a slip joint at the front and clamp joints at the sides of the furnace front.

Other features and advantages of the invention will appear from the following description, taken in connection with the drawings, wherein:

Figure 1 is a vertical cross section showing the furnace.

Figure 2 is a similar section showing the lower portion of the furnace with a forced draft air duct entering the rear thereof.

Figure 3 is a cross section through the upper part of the furnace on line 3-3 of Figure 1.

Figure 4 is a similar section showing a portion of the fire box with a plate connecting the outer ends of the corrugations.

Figure 5 is also a similar section showing a fire box divided into two parts with two flue openings.

Figure 6 is also a similar section showing corrugations of a different shape.

Figure 7 is a detail showing the means for connecting the ends of the sides of the corrugations to the top and bottom.

Figure 8 is a similar view showing the edge of the plates.

Figure 9 is a detail showing the means of connecting the lower portion of the outer 10 casing to the furnace front.

In the drawings the furnace is shown as it would be made wherein numeral 1 indicates the inner air heating chamber, numeral 2 the fire box, and numeral 3 the outer chamber.

In the structure shown the inner chamber is formed with a cylindrical casing 4 having a cone 5 at the lower end, and it is understood that although this is shown in a cylindrical shape it may be oval, square or of any other suitable shape. The cone 5 is provided with passages 6 which extend through the fire box 2 and through the wall 7 which forms the wall of the lower portion of the fire box.

2. At the lower end and at the front of the fire box 2 is a passage 8 which connects to the furnace front 9 and is provided with a door 10 having a ventilator 11 therein. At the rear of the casing is a duct 12 through which a gravity flow of air will pass into the casing. A feeder pipe 13 extends through the door to a burner as shown in Figure 1 and the outer end of the feeder pipe 13 may be connected by a pipe 14 to any suitable fuel supply. The fire box extends upward as a cylinder to the point 15 and at this point the actual walls of the fire box are corrugated or provided with channels 16 and it will be observed that the flames and hot gases from

40 the fire will travel upward until they strike the cone 5 and then be deflected outward so that they will pass upward through the channels 16. These channels may be triangular shaped as shown in Figures 3, 4, and 5 or of 45 a rectangular shape as shown in Figure 6 or of any other suitable shape. It will be noted that on the opposite side of the walls of the channels 16 are other channels which are indicated by the numeral 17 which may be

50 known as exterior or air channels and the air in the outer chamber 3 will pass upward through these channels with considerable velocity as the space between the walls of the channels will be heated to a very high temperature and the air therein will pass upward.

55 At the same time the air in the chamber 1 will also pass upward with considerable velocity as this chamber will also be heated to a very high temperature and it will therefore be possible to heat a large quantity of air to a very high temperature in a very short time so that a comparatively small furnace will have considerable capacity. The furnace will also have a maximum efficiency as the area of the 60 fire box is comparatively small owing to the

fact that the fire box is distributed through a plurality of vertical chambers so that the surface area of the fire box walls is very large and as the exterior of these walls form direct heating surfaces with the air to be heated coming into direct contact with them, a heating surface of a very large area in comparison with the size of the furnace is provided.

70 The burner on the pipe 13 may be positioned as shown in Figure 1 so that the gas will be ignited thereby forming a combustion chamber at the point 18 which will be directly below the cone 5 and the cone 5 will spread the flames and hot gases equally so that they will pass upward through the channels 16 and then downward through openings 19 in the walls of two of the channels into a box 20 formed between the channels and from the box 20 the gases may escape 80 through a pipe 21 to a stack. It will be noted that the hot gases will pass upward on the interior or around the casing 4 and as this space and also the upper ends of the channels 16 are closed these gases will pass outward and downward through the outer part of the channels 16 and as their only escape is through the box 20 at the stack opening, and also as they will be drawn by the stack 90 draft they will find their way to this point 95 and escape to the stack.

100 The chamber 3 is enclosed with a casing having a joint at the front as shown in Figure 3 in which one end of the casing is bent around and under to form a slot 22 into which the other end 23 will slide and the outer surface of the ends is provided with clips 24 and 25 which are held together by a bolt 26 so that as the nut on the bolt is tightened the end 23 will be forced into the slot 22 making a positive joint which will at the same time draw the two sides of the casing together. When it is desired to remove the inner part of the furnace the bolt 26 may be 105 removed so that the ends will open and these ends may be opened to the position indicated by the dotted lines 27 so that the inner part of the furnace may be removed through the front of the casing. The lower portion of the casing may be attached to the furnace front 9 by channel shaped clips 28 as shown in Figure 9. The ends of the lower portion of the casing which are indicated by the numerals 29 are provided with flanges 30 which will be held in the position shown in dotted lines in Figure 9 and it will be observed that as a nut 31 on a bolt 32 is tightened it will draw the member 28 downward to the position shown in full lines and this will draw the end 29 of the casing to the position shown 110 in full lines also so that the casing will be drawn into place and rigidly held.

115 The ends of the plates forming the walls between the channels 16 and 17 may be made as shown in Figures 7 and 8 in which the 120

plate 33 which forms the top of the furnace fire box and which is beveled so that it will slope downward at the upper end and upward at the lower end is provided with flanges 34 the upper edges of which are horizontal as shown so that the upper ends of the plates which are indicated by the numeral 35 and which form the walls between the channels 16 and 17 may be crimped over the edges 10 of the flanges 34 as shown. This will make it possible to form a tight joint without cutting and bending the ends of the vertical plates or a bevel.

In the structure shown in Figure 2 the lower portion of the furnace is provided with a forced draft intake duct 36 which opens into a chamber 37 surrounded by a wall 38 which extends upward to the lower end of the channels 16 and 17 so that as air is 15 forced in through this duct it will pass upward through the channels 16 and 17 and also through the openings 6 in the lower end of the chamber 1. It is understood that although the forced air duct is shown in this 20 manner it may be arranged in any other suitable manner and any other suitable connections may be provided between the duct and the upper portion of the furnace.

In the structure shown in Figure 4 the channels 16 and 17 are provided with an outer covering 39 which may extend continuously around the channels so that the outer ends of the channels will be closed thereby forming closed air spaces within the channels. 25

In the structure shown in Figure 5 the channels may be divided into two sections with partitions 40 and 41 connecting the inner edges of the channels to the wall 4 of the chamber 1 so that the fire box will be divided into two compartments and each compartment may be provided with a vent as indicated by the numerals 42 and 43. In this 30 design the furnace may be provided with a single burner as shown in Figure 1 or with two burners as shown in Figure 5 with each burner under a section of the fire box. It is also understood that the two burners may be used with the structure shown in Figure 1 or 35 with any of the other designs as may be desired.

A moisture pan as indicated by the numeral 44 may be provided in the wall of the upper part of the casing as shown in Figure 1. 40

It will be understood that changes may be made in the construction without departing from the spirit of the invention. One of which changes may be in the general design or shape of any of the parts, another may be in the location or arrangement of the stack connection, another may be in the arrangement or general design of the casing, and still another may be in the location or arrangement of the burner. 45

The construction will be readily understood from the foregoing description. To use the device it may be assembled as shown and it will be observed that as the gas is ignited at the burner 13 the flames and hot 70 gases will pass upward through the fire box as hereinbefore described and all the walls thereof will be heated to a very high temperature so that the air in the chamber 3 will circulate upward through the chamber 1 and the channels 17 so that its temperature will be rapidly raised to a very high degree and this air may be taken with suitable ducts to any desired point. The circulation may be increased if desired by forcing air in through 75 the duct 36 so that it will be forced into the channels and chamber 1. It will therefore be observed that the furnace of the highest possible efficiency will be obtained as the fire box is limited to a plurality of walls with air contacting the outer surfaces so that the heat will be directly transmitted to the air and the air currents will pass upward with considerable velocity so that a large quantity of air may be rapidly raised to a very high temperature. It will be observed that with a furnace of this type there is no grate or fire pot and it would be impossible to install a fire pot with this type of construction so that the furnace is only adaptable for burning gas or the 80 like or for a gas stove.

Having thus fully described the invention, what I claim as new and desire to secure by Letters Patent, is:—

In a furnace of the character described, an inner cylindrical chamber having a conical shaped lower end, an intermediate cylindrical shaped chamber with the portion thereof surrounding the straight portion of the said inner chamber corrugated by forming the wall thereof in a zig zag form, said intermediate chamber having an opening at the bottom and in one side with an enclosure around the said opening forming a fire box, comparatively large tubes extending from the conical portion of the inner chamber through the walls of the said intermediate chamber, the aggregate area of the said tubes being substantially equal to the cross section area of the said inner chamber, a jacket surrounding the said intermediate chamber and forming an outer casing to the upper portion of which connections may be made to convey the heated air therefrom to remote points, a burner positioned directly below the conical portion of the said inner chamber, and a stack connection boxed in between the corrugations of the said intermediate chamber at the lower end of the said corrugations and connecting to the said intermediate chamber through openings in the walls of the said corrugations. 100
